FRICITION LATCH MECHANISM
Carl E. Hafstad, 828 21st Ave. S., Minneapolis 4, Minn.
Filed Jan. 25, 1961, Ser. No. 84,829
8 Claims. (Cl. 292—76)

This invention relates generally to door latch mechanisms, and more particularly it relates to an improved and useful friction catch of a type which will yield under the application of force, as distinguished from the more positive type of locking catches.

More specifically my invention relates to friction latch mechanisms for use on storm doors and the like, which are usually provided with positive locking mechanisms. It is very often true that when doors of the above described class are provided with positive locking means, they are prevented from making locking engagement by the air pressure built up between the same and the inner door or other door with which they are associated, said pressures either being created by the closing movements of one or the other of said doors. Of course, under such conditions it is very possible that a situation is presented which the storm door may easily be broken or otherwise damaged since the same is not in a positively locked condition. In light of the above, it is an important object of this invention to provide an improved friction latch mechanism which may be used either with or without conventional positive locking latch mechanisms to overcome the conditions and disadvantages described above.

Another important object and advantage of this invention is the provision of an improved friction latch mechanism in which the force required to open the door with which it is associated is materially greater when certain parts or elements of said latch mechanisms are disposed in one position or condition than the force required to open said door when said parts or elements of said latch mechanism are disposed in another condition or position.

Another object of this invention is the provision of an improved friction latch mechanism in which the above described greater or additional force required to open said door when said latch mechanism is in a chosen position or condition may be easily and quickly reduced or avoided by the person opening the door.

Another object of this invention is the provision of an improved friction latch mechanism in which the same is adjustably and removably maintained in said position or condition wherein a materially greater force is required to open said door, and in which the maintenance of said additional force may be easily and quickly rendered inoperative by the operator of said latch mechanism.

Other objects of this invention reside in the provision of an improved friction latch mechanism which is extremely simple in construction, relatively inexpensive to manufacture, durable and strong throughout its continued use, simple and efficient in its operation, and highly efficient in sustaining the above stated purposes.

The above and still further objects of this invention will become apparent from the following detailed specification, appended claims and attached drawings.

Referring to the drawings wherein like reference characters indicate like parts or elements throughout the several views:

FIG. 1 is a view of my invention in front elevation, and showing portions of cooperating door and jamb members with which my novel friction latch mechanism is associated;

FIG. 2 is a view in section taken on the line 2—2 of FIG. 1, and showing my invention substantially in side elevation, some parts being broken away;

FIG. 3 is a view in section taken on the line 3—3 of

2

FIG. 2, and showing my invention substantially in rear elevation;

FIG. 4 is a view in section taken on the line 4—4 of FIG. 1 with some parts being broken away, and showing my novel latch mechanism in its closed position;

FIG. 5 is a view similar to FIG. 4, but showing the door member during initial opening movement thereof, and also showing portions of my novel latch mechanism in a position or condition resulting from opening of the door member from the outside thereof;

FIG. 6 is a view similar to FIG. 5, but showing said portions of my latch mechanism in a position or condition resulting from the opening of the door member from the inside thereof, and also showing other portions or elements of my invention in an alternative position;

FIG. 7 is a view similar to FIGS. 5 and 6, but showing the door member during final closing movement thereof, and also showing portions of my invention in their respective positions during final closing movement 20 of the door member; and

FIG. 8 is a view in horizontal section taken on the line 8—8 of FIG. 1.

Referring with greater particularity to the drawings, the door member, represented generally by the reference letter A, is movably mounted in a jamb member, which is represented generally by the reference letter B. A conventional keeper element 1 is rigidly secured to the inner face b of the jamb member B, near the outer edge c thereof, by means of a pair of screws 2. This invention resides specifically in the provision of a friction catch, which is represented generally by the reference numeral 3, the complete latch mechanism including the keeper element 1, being represented generally herein by the reference numeral 4. Also, the inner face of the door member A is represented by the reference letter a, the outer face thereof by the reference letter c, and the free edge of the door member A being represented by the reference letter e.

In accordance with my invention, the latch mechanism 40 4 comprises a rigid supporting housing, represented generally by the reference numeral 5, said supporting housing 5 including a front wall 6, an inner side wall 7, a top wall 8, a bottom wall 9, and securement flanges 10 for rigidly securing the supporting housing 5, by means of the fasteners 11, to the inner face a of the door member 45 A. It is noted that the back of the supporting housing 5 is generally open, and the supporting housing 5 is also bifurcated at the outer side 12 thereof so as to define spaced and alignable spring-carrying flanges 13. As shown, a pair of elongated coil springs 14, 15 are carried by the spaced flanges 13 of the supporting housing 5 so as to dispose the respective end portions 16, 17 of said springs 14, 15 in a fixed relationship with respect to the door member A. It is noted that the respective end portions 16, 17 of the coil springs 14, 15 are rigidly secured, as by welding or soldering, in the respective positions shown particularly in FIGS. 2, 3, and 8, said end portions 16 of the coil spring 14 being engaged with the arcuate end portions 18 of the flanges 13 and the end portions 17 of the coil spring 15 being engaged with the corner defined by the flanges 13, and the outer side 12 and the front wall 6 of the supporting housing 5.

An important part of my invention concerns the respective positions of the elongated coil springs 14, 15, and 65 also the provision of means for selectively changing the respective positions between the coil springs 14, 15. More specifically, one respective position or condition of the springs 14, 15 are disposed in generally laterally spaced generally parallel relationship with one another. It is 70 noted with particularly emphasis that the coil springs 14, 15 when the same are in said one condition are thereby

so orientated that the coil spring 14 is engaged by the keeper element 1 during initial opening movement of the door member A with respect to the jamb member B so that lateral deflection is imparted to the spring 14 in a direction generally toward the spaced spring 15. Said engagement of the spring 14 by the keeper element 1 and the resulting deflection of the spring 14 during initial opening movement of the door member A is shown particularly in FIG. 6. It is noted with emphasis that the opening force required to open the door member A when the springs are in said spaced one condition is only the force needed to deflect the coil spring 14 to the position shown in FIG. 6 since the coil spring 15 is not deflected in said one condition of the springs 14, 15.

For the purpose of providing means for selectively adjusting the coil springs 14, 15 so as to define a second condition or relative position of said coil springs 14, 15, a slide element, represented generally by the reference numeral 19, is mounted on the supporting housing 5. The slide element 19 generally comprises an elongated bar, which defines a projecting knob 21 on one side thereof and a projecting dog 22 on the other side thereof. The knob 21 has a flange portion 23 which is maintained in spaced relationship with the bar of the slide element 19 by means of a stub journal 24, said knob 21 being removably secured to the slide element 19 by means of a screw 25. As shown particularly in FIGS. 1 and 4, the front wall 6 of the supporting housing 5 defines an elongated slot 26, which slot 26 is adapted to receive the stub journal 24 of the slide element 19 so that the bar of the slide element 19 is disposed in face-to-face sliding relationship with the inner surface of the front wall 6 of the supporting housing 5 and so that the flange portion 23 of the knob 21 is disposed in sliding face-to-face relationship with the outer surface of the front wall 6 of the supporting housing 5. Referring particularly to FIGS. 2 and 4, the slide element 19 also defines an abutment surface 27 on the end thereof disposed adjacent the coil spring 15. The above described construction is such that the slide element 19 is thereby mounted on the supporting housing 5 for movement toward and away from the coil spring 15 between a spaced position in spaced relationship to said coil spring 15 (as shown in FIG. 6) and an engaged position (as shown in FIGS. 2 and 4) wherein the abutment surface 27 of the slide element 19 is disposed in engagement with a generally intermediate portion 28 of the coil spring 15. Such an engagement between the abutment surface 27 and said intermediate portion 28 of the coil spring 15 into engagement with the coil spring 14 and thereby defines a second relative condition of the coil springs 14, 15.

For the purpose of providing yielding means to be associated with the supporting housing 5 and the slide element 19 for biasing said slide element 19 toward the above described engaged position thereof in engagement with the coil spring 15 so as to removably maintain both of said coil springs 14, 15 in the above described second condition or position thereof shown in FIGS. 2 and 4, a compression spring 29 is interposed between a detent 30 defined on the dog 22 of the slide element 19 and an opposed and aligned detent 31 defined by the side wall 7 of the supporting housing 5. In the position of the compression spring 29 shown and described, the axis thereof is disposed in general normality to the longitudinal axes of the elongated coil springs 14, 15 so that the coil spring 15 is normally biased in such manner as to define the above described second condition or relative position of the coil springs 14, 15. It should be noted with particular emphasis that when the coil springs 14, 15 are in the above described second relative condition thereof, they are thereby orientated so that the coil spring 14 is engaged by the keeper element 1 during initial opening movement of the door member A with respect to the jamb member B so that generally concerted lateral deflection is imparted to both of the coil springs 14, 15 during said initial open-

ing movement of the door member A. More specifically with respect to the deflection of the coil springs 14, 15 during the initial opening movement of the door member A when the coil springs 14, 15 are in said second condition thereof, the coil spring 15 is actually deflected by the keeper element 1 and said deflection is then imparted to the engaged intermediate portion 28 of the coil spring 15 so as to move said intermediate portion 28 of the coil spring 15 along the abutment surface 27 of the slide element 19 during said initial opening movement of the door member A. It should be stated that in accordance with present practices, the orientation of the coil springs 14, 15 when the same are in either the above described one condition thereof or the second condition thereof is such that lateral deflection is imparted only to the coil spring 14 during final closing movement of the door member A with respect to the jamb member B, as shown in FIG. 7.

Having specifically described my invention, it might be helpful to comment with respect to the operative simplicity thereof. Generally speaking, a novel friction catch 3 has been provided in which the force required to open the door member A upon which the friction catch 3 is secured is materially less when the friction catch 3 is in said above described one condition than the force required to open the door member A when said friction catch 3 is in another second condition thereof. More specifically, FIG. 4 of the drawings shows the latch mechanism 4 and the door member A in the closed position thereof, and FIG. 5 is illustrative of a position of the friction catch 3 during initial opening movement of the door member A when the door member A is opened from the outside thereof, it being understood that the terminology "inside" and "outside" corresponds to the inner face *a* and the outer face *b* of the door member A. The illustration of FIG. 5 is intended to correspond to the situation described in the introduction to this specification wherein it is desirable that a materially greater force be required to open the door member A from the outside thereof than the force required to open the door member A from the inside thereof, the terminology "outside" and "inside" not being intended to be a limitation with respect to the relative positioning of the door member A with respect to the jamb member B, but only being given the connotation described above. It is noted therefore with respect to FIG. 5 that the friction catch 3 is shown therein in the above described second condition thereof so that the opening of the door member A from the outside thereof requires a deflection of both of the coil springs 14, 15.

Referring to FIG. 6, the same is illustrative of the conditions present when it is desired to open the door member A from the inside thereof, the obnoxious pressure (noted in the introduction to this specification) between the door member A and another door (not shown, and associated with the jamb member B) being obviously previously released in this situation by the opening of said other door. It will be noted with respect to FIG. 6 that when the knob 21 of the slide element 19 is moved in a direction away from the coil spring 15, the abutment surface of the slide element 19 is removed from its engagement with the generally intermediate portion 28 of the coil spring 15 and the coil springs 14, 15 are then disposed in the above described one condition thereof wherein said springs 14, 15 are in laterally spaced generally parallel relationship. Obviously, in this condition of the springs 14, 15, the force required to open the door member A need only be sufficient to deflect the coil spring 14. It should also be noted that FIG. 7 is illustrative of the position of the friction catch 3 during final closing movement of the door member A. In this situation, only a relatively small force is required to close the door member A, without regard to whether the coil springs 14, 15 are disposed in either of the above described one condition or second condition thereof. Obviously, the coil springs 14, 15 of the friction catch 3 will usually be

disposed in the second above described spaced condition thereof shown particularly in FIGS. 4, 5 and 7, this being due to the biasing of the slide element 19 toward the coil spring 15 by the compression spring 29.

This invention has been thoroughly tested and found to be completely satisfactory for the accomplishment of the above objects; and while I have shown and described above a preferred embodiment thereof in which the principles of the present invention have been incorporated, I wish it to be specifically understood that the same may be modified without departure from the scope and spirit of the appended claims.

What I claim is:

1. In a latch mechanism for latching a door member mounted for opening and closing movements relative to a cooperating jamb member, and in which one of said members is provided with a rigidly mounted keeper element, the improvement of a friction catch, said improvement comprising supporting structure rigidly secured to the other of said members, a pair of elongated coil springs carried by said supporting structure with their respective end portions fixedly disposed with respect to said other of said members, said springs being disposed in one condition in generally laterally spaced generally parallel relationship with one another, said coil springs when in said one condition being so orientated that one of said springs is engaged by said keeper element during initial opening movement of said door member with respect to said jamb member so that lateral deflection is imparted to said one spring, and a movable abutment element mounted on said supporting structure for movements toward and away from said other of said springs between a spaced position in spaced relationship to said other of said springs and an engaged position wherein said abutment element is disposed in engagement with a generally intermediate portion of said other of said springs so as to displace said intermediate portion of said other of said springs into engagement with said one of said springs and thereby define a second condition of said springs, said coil springs when in said second condition being so orientated that said one spring is engaged by said keeper element during initial opening movement of said door member with respect to said jamb member so that concerted lateral deflection is imparted to both of said coil springs during said movement, whereby the force required to deflect both of said springs and open said door member when said springs are in said second condition is materially greater than the force required to deflect said one spring and open said door member when said springs are in said one condition.

2. In a latch mechanism for latching a door member mounted for opening and closing movements relative to a cooperating jamb member, and in which one of said members is provided with a rigidly mounted keeper element, the improvement of a friction catch, said improvement comprising supporting structure rigidly secured to the other of said members, a pair of elongated coil springs carried by said supporting structure with their respective end portions fixedly disposed with respect to said other of said members, said springs being disposed in one condition in generally laterally spaced generally parallel relationship with one another, said coil springs when in said one condition being so orientated that one of said springs is engaged by said keeper element during initial opening movement of said door member with respect to said jamb member so that lateral deflection is imparted to said one spring, and a movable abutment element mounted on said supporting structure for movements toward and away from said other of said springs between a spaced position in spaced relationship to said other of said springs and an engaged position wherein said abutment element is disposed in engagement with a generally intermediate portion of said other of said springs so as to displace said intermediate portion of said other of said springs into engagement with said one of said springs and thereby

define a second condition of said springs, said coil springs when in said second condition being so orientated that said one spring is engaged by said keeper element during initial opening movement of said door member with respect to said jamb member so that generally concerted lateral deflection is imparted to both of said coil springs during said movement, whereby the force required to deflect both of said springs and open said door member when said springs are in said second condition is materially greater than the force required to deflect said one spring and open said door member when said springs are in said one condition, the orientation of said coil springs when the same are in a selection of said one condition and said second condition being such that lateral deflection is imparted only to said one spring during final closing movement of said door member with respect to said jamb member.

3. In a latch mechanism for latching a door member mounted for opening and closing movements relative to a cooperating jamb member, and in which said jamb member is provided with a rigidly mounted keeper element, the improvement of a friction catch, said improvement comprising a supporting housing rigidly secured to said door member, a pair of elongated coil springs carried by said supporting housing with their respective end portions fixedly disposed with respect to said door member, said springs being disposed in one condition in generally laterally spaced generally parallel relationship with one another, said coil springs when in said one condition being so orientated that one of said springs is engaged by said keeper element during initial opening movement of said door member with respect to said jamb member so that lateral deflection is imparted to said one spring, and an abutment-surface-defining slide element mounted on said supporting housing for movements toward and away from said other of said springs between a spaced position in spaced relationship to said other of said springs and an engaged position wherein the abutment surface of said slide element is disposed in engagement with a generally intermediate portion of said other of said springs so as to displace said intermediate portion of said other of said springs into engagement with said one of said springs and thereby define a second condition of said springs, said coil springs in said second condition being so orientated that said one spring is engaged by said keeper element during initial opening movement of said door member with respect to said jamb member so that concerted lateral deflection is imparted to both of said coil springs during said movement, whereby the force required to deflect both of said springs and open said door member when said springs are in said second condition is materially greater than the force required to deflect said one spring and open said door member when said springs are in said one condition.

4. The structure defined in claim 3 in which the orientation of said coil springs when the same are in a selection of said one condition and said second condition is such that lateral deflection is imparted only to said one spring during final closing movement of said door member with respect to said jamb member.

5. In a latch mechanism for latching a door member mounted for opening and closing movements of its free edge relative to a cooperating jamb member, and in which said jamb member is provided with a rigidly mounted keeper element, the improvement of a friction catch, said improvement comprising a supporting housing rigidly secured to said door member, a pair of elongated coil springs carried by said supporting housing with their respective end portions fixedly disposed with respect to said door member, said springs being disposed in one condition in generally laterally spaced generally parallel relationship with one another, said coil springs when in said one condition being so orientated that one of said springs is engaged by said keeper element during initial opening movement of said door member with respect to said jamb member.

member so that lateral deflection is imparted to said one spring, an abutment-surface-defining slide element mounted on said supporting housing for movement toward and away from said other of said springs between a spaced position in spaced relationship to said other of said springs and an engaged position wherein the abutment surface of said slide element is disposed in engagement with a generally intermediate portion of said other of said springs so as to displace said intermediate portion of said other of said springs into engagement with said one of said springs and thereby define a second condition of said springs, and yielding means associated with said supporting housing and said slide element for biasing said slide element toward said engaged position thereof, said coil springs when in said second condition being so orientated that said one spring is engaged by said keeper element during initial opening movement of said door member with respect to said jamb member so that generally concerted lateral deflection is imparted to both of said coil springs during said movement, whereby the force required to deflect both of said springs and open said door member when said springs are in said second condition is materially greater than the force required to deflect said one spring and open said door member when said springs are in said one condition.

6. The structure defined in claim 5 in which the orientation of said coil springs when the same are in a selection of said one condition and said second condition is such that lateral deflection is imparted only to said one spring during final closing movement of said door member with respect to said jamb member.

7. The structure defined in claim 5 in which said supporting housing has opposite sides, said elongated coil springs being carried by said supporting housing on the side thereof disposed adjacent the free edge of said door member, and in which said yielding means comprises: a dog defined by said slide element and projecting into said supporting housing; a detent defined by the side of said housing opposite the side thereof which carries said elongated coil springs; and a compression spring interposed between said dog and said detent and disposed with its axis in general normality to the axes of said elongated coil springs.

8. In a latch mechanism for latching a door member mounted for opening and closing movements relative to a cooperating jamb member, and in which said jamb member is provided with a rigidly mounted keeper element, the improvement of a friction catch, said improve-

ment comprising a supporting housing rigidly secured to said door member, a pair of elongated coil springs carried by said supporting housing on the side thereof disposed adjacent the free edge of said door member and with the respective end portion of said coil springs being fixedly disposed with respect to said door member, said springs being disposed in one condition in generally laterally spaced generally parallel relationship with one another, said coil springs when in said one condition being so orientated that one of said springs is engaged by said keeper element during initial opening movement of said door member with respect to said jamb member so that lateral deflection is imparted to said one spring in a direction generally toward said spaced other spring, an abutment-surface-defining slide element mounted on said supporting housing for movement toward and away from said other of said springs between a spaced position in spaced relationship to said other of said springs and an engaged position wherein the abutment surface of said slide element is disposed in engagement with a generally intermediate portion of said other of said springs so as to displace said intermediate portion of said other of said springs into engagement with said one of said springs and thereby define a second condition of said springs, and yielding means associated with said supporting housing and said slide element for biasing said slide element toward said engaged position thereof, said coil springs when in said second condition being so orientated that said one spring is engaged by said keeper element during initial opening movement of said door member with respect to said jamb member so that said one spring is deflected and said deflection is imparted to said engaged intermediate portion of said other spring so as to move said intermediate portion of said spring along the abutment surface of said slide element during said initial opening movement, whereby the force required to deflect both of said springs and open said door member when said springs are in said second condition is materially greater than the force required to deflect said one spring and said door member when said springs are in said one condition.
